Patented Aug. 22, 1961

191,161

FOUNDATION SKID FOR PORTABLE BUILDINGS OR THE LIKE

Floyd E. Bigelow, Jr., 716 W. 16th St., Houston, Tex.

Filed June 27, 1960, Ser. No. 61,123

Term of patent 14 years

(Cl. D13—1)

FIGURE 1 is a perspective view of a foundation skid for portable buildings; or the like, showing my new design;

I claim:

The ornamental design for a foundation skid for portable buildings or the like, as shown.
